UNITED STATES PATENT OFFICE

151,731

DESIGN FOR A BROOCH OR SIMILAR ARTICLE

Octave Blake, Plainfield, N. J.

Application May 14, 1948, Serial No. 146,384

Term of patent 14 years

(Cl. D45—19)

To all whom it may concern:

Be it known that Octave Blake, a citizen of the United States, residing at Plainfield, in the county of Union and State of New Jersey, has invented a new, original, and ornamental Design for a Brooch or Similar Article, of which the following is a specification, reference being had to the accompanying drawings, forming a part thereof wherein:

Figure 1 is a plan view of a brooch, showing my new design and,

Figure 2 is a perspective view of a brooch, showing my new design.

I claim:

The ornamental design for a brooch or similar article, substantially as shown.

OCTAVE BLAKE.
